UNITED STATES PATENT OFFICE.

WILLIAM DZIEZYC, OF MIDDLETOWN, NEW JERSEY.

WIRE-ENTANGLEMENT CUTTER FOR BAYONETS.

1,274,019.

Specification of Letters Patent. Patented July 30, 1918.

Application filed November 22, 1917. Serial No. 203,364.

To all whom it may concern:

Be it known that I, WILLIAM DZIEZYC, a citizen of Russia, residing at Middletown, in the county of Monmouth and State of New Jersey, have invented certain new and useful Improvements in Wire-Entanglement Cutters for Bayonets, of which the following is a specification.

This invention relates to certain new and useful improvements in wire entanglement cutters for bayonets.

The primary object of the invention is the provision of a device adapted for ready attachment to the bayonet of a fire arm, whereby the soldier may readily cut a wire entanglement for clearing the same away from the line of march.

A further object of the device is to provide wire cutting scissors with a detachable clamping means whereby the scissors are operatively positioned upon a sharpened bayonet or blade ready for use in cutting wires and operable by the soldier from a point adjacent the fire arm upon which the blade is mounted.

A still further object of the device is the provision of a resilient retaining means for a blade whereby a desirable member may be securely locked thereto and removed therefrom at will while the elements are inseparable when the device is in closed engagement.

In the drawing forming a part of this application and in which like reference characters designate corresponding parts throughout the several views,

Figure 1 is an elevational view of the device arranged upon a bayonet.

Fig. 2 is a top plan view thereof.

Fig. 3 is a sectional view through a portion of the device adjacent the locking clamp.

Fig. 4 is a transverse sectional view taken upon line IV—IV of Fig. 1.

Fig. 5 is a detail view taken partly in section upon line V—V of Fig. 4, and

Fig. 6 is a perspective view of the clamp detached with portions thereof broken away.

It being understood that the device is adaptable for war purposes in cutting wire, the same broadly consists of a pair of wire cutting scissors or shears 10 adapted for detachable locking engagement with a double edged bayonet 11 of a rifle, not shown. The shears 10 consist of handles 12 and 13 shiftably connected together by a

pivot 14 and formed with cutting jaws 15 and 16 respectively. The jaw 16 has a convex cutting edge 17 terminating in a socket 18 adjacent the pivot 14 while the cooperating edge 19 of the jaw 15 is of general concave form having a socket 20 adjacent the pivotal point. In operation, a wire such as 21 is adapted to be received within the sockets 18 and 20 and the handle 13 is shifted upon the pivot 14 by means of a pull cord 22 secured adjacent the free end of the said handle and extending to a point in the hand of the operator or soldier carrying the fire arm which is provided with the bayonet 11. By pulling the cord 22, the jaws 15 and 16 are moved toward each other upon the wire 21 for severing the wire.

The handle 12 of the shears 10 is provided with a loop 23 for receiving the pointed free end portion 24 of the bayonet 11 while a resilient locking clamp 25 secured adjacent the free end of the handle 12 is adapted to retainingly inclose the blade 11, thereby mounting the shears 10 thereon as indicated in Fig. 1 of the drawing.

The clamp 25 is preferably formed of resilient sheet metal having a substantially V-shaped base member 26 with a central flat portion 27 secured by rivets 28' to the handle 12. A resilient cover plate 28 is hinged as at 29 to the free edge of one side 30 of the base 26, the said plate having a wide receiving hook 31 formed therein intermediate its ends by bending the said plate 28 and adapted to spring over an outturned flange 32 at the free edge of the opposite lip 33 of the base side 34.

The plate 28 is readily swung to its open position upon the hinge 29 for receiving the bayonet 11 within the clamp 25 resting upon the base 26 inwardly of the lip 33 thereof. The sides 30 and 34 are sprung toward the handle 12 thereby depressing the outwardly struck lugs 35 thereof into engagement with the handle 12. The lip 33 is then depressed toward the bayonet 11 and the cover plate 28 folded over the bayonet and the hook 31 sprung over the flange 32, thereby inclosing the bayonet within the clamp 25 with one of its edges 36 within the V-shaped side 37 formed between the lip 33 and base side 34, while the opposite edge 36 of the bayonet is positioned within a similar recess formed adjacent the hinge 29 by the plate 28 and the base side 30.

When the clamp 25 is closed in this man-

ner, the bayonet 11 is securely held thereby for operatively maintaining the shears 10 upon the bayonet while a link 38 swingingly carried by the resilient end portion 39 of 5 the cover plate 28 is engaged over a keeper 40 carried by the handle 12. The plate portion 39 is slightly bent when the link 38 is forced over the keeper 40, so that the sides 30, 34 of the clamp 25 as well as the lip 33 10 and the cover plate 28 are resiliently engaged with the bayonet 11 when the clamp is closed, it being seen that the inner dimensions of the clamp are thereby reduced as shown by Figs. 3 and 4 of the drawing. 15 The shears 10 may be readily detached from the bayonet 11 by releasing the link 38 and opening the clamp 25, permitting the bayonet to be withdrawn from the clamp and also from the loop 23. The device is of 20 light weight and may be easily carried by a soldier and quickly locked upon the bayonet of his rifle for cutting wires such as barbed entanglements whenever the occasion may arrive.

25 What I claim as new is:—

1. In combination with a wire cutting shears having a handle adapted for attachment to a bayonet, a clamp formed of resilient sheet metal comprising a substantially V-shaped base secured to the handle and arranged with struck-out lugs adjacent the handle, an inturned lip upon one side of the base forming a V-shaped receiving space for one side of the bayonet, an outwardly projecting flange at the free end of the lip, a cover plate of resilient metal hinged to the other side of the base having a bent hooked portion intermediate its ends adapted for springing over the said flange in retaining engagement therewith when the base lip and plate are resiliently engaged with the bayonet when the clamp is closed thereon, the said plate having a resilient end portion outwardly of said hook, a swinging link 40 carried by the free end of the cover plate 45

and a keeper upon the handle adapted for receiving the said link when the clamp is closed.

2. A wire cutting attachment comprising in combination with a bayonet, a wire cutting shears having a mounting handle and an operating handle, a pull cord attached to the operating handle, a loop upon the attaching handle adapted for the reception of the pointed end portion of the bayonet, a resilient bayonet receiving clamp upon the attaching handle, resilient closing means for the clamp and retaining means for the latter when closed, whereby the clamp is retained upon the bayonet with the sides of the clamp 50 in tensioned engagement therewith.

3. A retaining clamp comprising a V-shaped base having opposite resilient sides, an inturned lip on one of said sides forming a V-shaped receiving portion, an outwardly 65 projecting flange upon said lip, a retaining plate hinged to the opposite side of the base having an intermediate bent portion in the form of a hook adapted for engagement over the said flange when the clamp is closed, 70 and an anchoring link swingingly carried by the free end of the said plate.

4. A mounting clamp for scissors formed of resilient sheet metal comprising a V-shaped base adapted for attachment to the handle of the scissors and provided with struck-out lugs adapted for seating upon the handle when the base is extended with the clamp in its closed position, an inturned lip carried by one side of the base terminating in a flange, a cover plate hinged to the opposite side of the flange having a hook portion adapted for engagement over the said flange when the clamp is closed, resiliently contacting an article arranged therein, 80 and locking means for the free end of said plate.

In testimony whereof I affix my signature.

WILLIAM DZIEZYC.
